(57) **CLAIM**

The ornamental design for an enclosure for a sweeper vehicle, as shown and described.

DESCRIPTION

FIG. 1 is a front perspective view of an enclosure for a sweeper vehicle showing my new design;

FIG. 2 is a front elevational view thereof;

FIG. 3 is a rear elevational view thereof;

FIG. 4 is a left side elevational view thereof; and,

FIG. 5 is a right side elevational view thereof.

The elements shown in phantom lines do not form any part of the design of the present invention.
